CLAIM

The ornamental design for a shoe, as shown and described.

DESCRIPTION

FIG. 1 is a side view of a shoe showing my new design;
 FIG. 2 is a rear perspective view thereof;
 FIG. 3 is a rear view thereof;
 FIG. 4 is an opposite side rear perspective view thereof; and,
 FIG. 5 is an opposite side view thereof.

The broken line showing of the diamond-shaped regions represent eyelets that form no part of the claimed design. The vertically-oriented broken line bisecting the rear of the shoe represents a seam which forms no part of the claimed design. The broken lines immediately adjacent to the bottom of the shaded area define the bounds of the claimed design and form no part thereof. The broken lines depicting the remainder of the shoe form no part of the claimed design.
